UNITED STATES PATENT OFFICE.

ROBERT J. ANDERSON, OF SIDNEY, OHIO.

PIVOTED WRINGER STRUCTURE FOR WASHING MACHINES.

1,417,656.

Specification of Letters Patent. Patented May 30, 1922.

Application filed August 22, 1917. Serial No. 187,598.

To all whom it may concern:

Be it known that I, ROBERT J. ANDERSON, a citizen of the United States, residing at Sidney, in the county of Shelby and State 5 of Ohio, have invented certain new and useful Improvements in Pivoted Wringer Structures for Washing Machines, of which the following is a specification.

It is the object of my invention to provide 10 a washing machine comprising a plurality of tubs arranged in side by side relation, to provide novel wringer mechanism for tubs so arranged comprising a standard located between said tubs and a bracket arranged 15 to support the wringer so pivoted as to locate the wringer in position to coact with either of said tubs; further, to provide novel means for rotating the wringer-rollers so that the wringer may be placed in coactive 20 relation with either of said tubs which is stationarily positioned and the wringer-rollers rotated selectively in either direction; further, to provide novel means whereby the wringer-rollers are rotated selectively in either direction; further, to provide novel means whereby the wringer is positioned selectively and for maintaining the 25 wringer in such relation.

The invention will be further readily understood from the following description and claims, and from the drawings, in which latter:

Fig. 1 is an end elevation of my improved device.

Fig. 2 is a cross-section of the same, taken on the line 2—2 of Fig. 3, and partly broken away.

Fig. 3 is a plan view of my improved device.

Fig. 4 is a rear elevation of the same.

Fig. 5 is an end elevation of the tub and its supporting means, the latter partly broken away, and showing the tub in assumed rocked positions in dotted lines.

Fig. 6 is a cross-section of the same, taken on the line 6—6 of Fig. 5.

Fig. 7 is a plan sectional detail of the shifting-means for the tub-operating clutches, on the line 7—7 of Fig. 2.

Fig. 8 is a cross-section of the driving means, taken on the irregular line 8—8 of Fig. 2.

Fig. 9 is a vertical section of the same, taken in the plane of the line 9—9 of Fig. 8.

Fig. 10 is a sectional detail of the same, taken on the line 10—10 of Fig. 8.

Fig. 11 is a vertical axial section of the driving mechanism for the wringer, taken on the line 11—11 of Fig. 1.

Fig. 12 is a cross-section of the same, 60 taken on the line 12—12 of Fig. 11.

Fig. 13 is a cross-section of the same, taken in the plane of the line 13—13 of Fig. 11; and,

Fig. 14 is a perspective view of the clamp- 65 ing arm for the wringer-bracket.

I have in the present exemplification of my invention, shown the tubs as of substantially elliptical form and as provided with balance springs arranged about the pivotal 70 axis of the tub, and have shown the tub pivoted at a point slightly below the center of the tub or center of the substantial ellipse on which the tub is formed, the pivotal axis of the tub being within the balance springs, 75 but I do not herein claim the tub structure, having shown described and claimed said structure in my copending application, filed Aug. 16, 1917 as Serial No. 186,622, nor do I herein claim the manner of mounting the 80 tub, or of the means for resiliently balancing the tub, or of pivoting the tub, having shown, described and claimed the same in my copending application filed Aug. 16, 1917, as Serial No. 186,623.

In the present exemplification of my invention I have instanced two washing tubs and a wringer arranged to be swung in position for use with either tub, it being understood that the wringing of the clothes 90 may be accomplished from or into either tub into or from a suitable tub or basket at the outside the tubs of the machine, or the wringer may be swung into intermediate position for wringing the laundry from one tub 95 into the other of the mechanism exemplified.

The tubs are shown at 21, 22, respectively, and are instanced as oscillating tubs, being mounted upon trunnions 23, fixedly extending from spiders 24 secured to the heads 25 100 of the tubs, and journaled in suitable bearings 26, 27. (See Figs. 3, 4 and 6). The bearings are on a supporting frame 28, comprising end frame-pieces 29, 30, and an intermediate frame-piece 31. The end frame-pieces comprise upwardly inwardly sloping sides 32, sloping toward each other, and connected by a top 33, to which the bearing 26 is secured. The intermediate frame-piece 105 comprises similarly sloping sides 34 connected by a top 35 to which a bearing-block 36 is secured, forming part of bearing 27.

The end frame-pieces and intermediate frame-piece are spaced apart and suitably connected as by means of brace-rods 41, 42, exemplified as bolted to said end frame-pieces and intermediate frame-piece, forming tub-receiving spaces between said frame-pieces and brace-rods.

5 A gear-housing 46 is secured to the intermediate frame-piece, by providing the same 10 with lugs 47, through which bolts 48 pass into the frame-piece. The gear-housing acts as an oil-container for containing a body of oil contacted by the gears in the housing.

15 A drive-shaft 49 is journaled in bearings 50 in said housing and in a bearing 51 on one of the end frame-pieces, suitable means being provided for rotating the drive-shaft, either manually or by power, a belt-receiving pulley 52 being instanced as secured to said 20 drive-shaft. (See Figs. 1, 4 and 8). A pinion 53 is fast on the drive-shaft and meshes with gears 54, 55, rotatable loosely on shafts 56, 57, journaled in bearings 58, 59, in the housing. The gears 54, 55, are held endwise 25 on their shafts between shoulders 60 on the respective shafts and one of the bearings thereof.

30 Arms 61, 62, are secured at opposite ends of said respective shafts and form crank-arms respectively provided with crank-pins 63, 64. Connecting-rods 65, 66, respectively have bearings 67, 68 about said crank-pins, the other ends of said connecting-rods being provided with bearings 71, 72, received about 35 stud-pins 73, 74, secured to the spiders 24. (See Figs. 2, 3, 4 and 8).

40 A clutch 81 is located between each of the respective gears 54, 55, and its shaft to which the crank-arm is fixed, for placing either tub or both tubs in operative connection 45 with its driving mechanism. (See Figs. 8 and 9). This clutch is instanced as comprising a collar 82, having spline-connection 83 with its shaft, for causing rotation of the shaft with the clutch and permitting axial movement of the collar, so as to engage the teeth of the clutch on the collar with the teeth of the clutch on the gear.

50 These teeth 84 are preferably flat-sided teeth, so as to move the shaft in either direction of movement of the gear, and the teeth are so arranged, as by providing two irregular teeth and corresponding recesses 85, that the gear and crank-arm are connected only 55 in one relation, so as to insure the proper timed oscillation of the tub or tubs. (See Fig. 10). This timed oscillation is preferably such that when both tubs are in motion they will oscillate together, the fronts of 60 the tubs descending together and rising together, avoiding confusion of and consequent injury to the operator. The clutch is preferably received in a hood 86 extending from the gear-housing.

65 The clutch is operated by means of a lever

87 pivoted by a pin 88 in lugs 89 of the cover 90 of the gear-housing and having a fork-end 91, the tines of which are received in an annular groove 92 of the collar 82. The cover 90 is secured to the housing by 70 screws 93.

The crank-arms and clutches for the respective gears 54, 55, are respectively at opposite sides of said gears, locating a crank-arm for one gear and a clutch for the other 75 gear at one side of said gears, in substantially the same vertical plane perpendicular to the axes of rotation of said gears, the remaining crank-arm and clutch being similarly placed at the other side of said gears, 80 thus providing compact arrangement of the parts between the tubs.

The respective levers 87 are operated from the front of the machine by means of handles 96, 97. (See Figs. 1, 2, 3, 4, 7 and 9). The 85 handle 96 has a rod 98 extending therefrom, which rocks in bearings 99 on the intermediate frame-piece, and has an arm 100 extending therefrom. A link 101 is articulated with the arm at 102 and with the 90 clutch-lever 87 for the gear 54 at 103 for operating the latter.

The handle 97 has a rod 105 extending therefrom, arranged to rock in bearings 106 on the intermediate frame-piece. The rod 95 105 has an arm 107 extending therefrom, a link 108 being articulated with the arm at 109 and with the clutch-lever for gear 55 at 110. The handles are arranged to selectively operate either or both clutches for selectively causing operation of either or of both 100 tubs. The clutches are so arranged that they can be connected only in one relation to cause both tubs to move in unison, when both clutches are in operative connection, the 105 forward ends of the tubs moving up or down together.

A column 111 extends upwardly with relation to the housing 46. It is secured to the main frame by means of lugs 112 thereon 110 which are bolted to the upright 113 of the intermediate frame-piece.

Brace-rods 114, 115, extend between the column and the end frame-pieces, being bent rearwardly, to avoid contact with the tubs. 115 The respective ends of the brace-rods are secured to the column and frame by bolts 117.

The column has a bearing 120 at its lower end for an upright shaft 121. (See Fig. 120 11). The upper end of the column is provided with a bushing 122, forming a trunnion, a shoulder 123 being located proximate to the lower end of said trunnion. A wringer-arm 126 is journaled by a bearing-sleeve 127 about the bushing and has a bearing 128 therein for the upright shaft. The upright shaft has a bevel-gear 129, fixed to its upper end. The bevel-gear supports the upright shaft in its bearings.

A shaft 131 is journaled in bearings 132 in the housing and has thereon a gear 133 and a bevel-gear 134, the gears 133, 134, rotating together. Gear 133 meshes with 5 gear 54.

The upright shaft has a bevel-gear 135 fast at its lower end, meshing with the bevel-gear 134. The upper end of the hub of bevel-gear 135 is arranged to contact the 10 lower end of the bearing 120 for maintaining meshing relation between the bevel-gears 134 and 135.

The wringer-arm is provided with a bracket 136 which may be provided with suitable 15 means for the attachment of a suitable wringer, exemplified at 137. The wringer is instanced as having a pair of rollers 138, 139, the roller 138 being the operated roller, instanced as having connection with the driving 20 mechanism of the machine by means of a cross-shaft 140, instanced as the shaft to which the lower roller is suitably secured, so as to be rotated thereby.

A yoke 141 is located above the bearing 128 25 of the wringer-arm, and has bearings 142 therein for the cross-shaft 140. (See Figs. 11 and 12.) Bevel-gears 143, 144, received about the cross-shaft, are normally loose thereon, and mesh with opposite sides of the bevel-gear 129. Clutches 145, 146, are arranged 30 to connect the cross-shaft and the respective bevel-gears 143, 144. The teeth of the respective clutches at opposite ends of a collar 147 are arranged to coact with coacting 35 teeth on said respective bevel-gears. The collar 147 has spline-connection 148 with said cross-shaft. In practice said bevel-gears 143, 144, are continually rotating during operation of the machine. The respective 40 clutches communicate motion to said cross-shaft and rotate said cross-shaft in opposite directions, whereby rotation of the wringer-rollers is effected in opposite directions for causing movement of the laundry therethrough from either tub into the other 45 or into or from either tub from or into a suitable receptacle, such as an auxiliary tub or basket, from or into which the clothes are passed from the wringer.

The clutches are preferably toothed-clutches and the teeth preferably have flat sides, so that the cross-shaft will be revolved regardless of the direction of rotation of the bevel-gear 129, it being understood that the 50 drive-shaft may be rotated in either direction for operating the tubs and wringer-rollers.

The clutch-collar 147 is arranged to be operated by means of a lever 149 having a fork 55 150, the tines of which are in an annular groove 151 in said clutch-collar. (See Figs. 11 and 12.) The lever 149 is pivoted on a bolt 152 in a gear-cover 153 having an upper plate 154 extending therefrom. A 60 spring 155 urges the upper end of the lever

toward the plate. The lever is provided with a positioning knob 156 coacting with positioning recesses 157 in said plate. The lever is fulcrumed on a rib 158 on the lever, so that the spring pushes the knob and recesses into 70 coaction for holding the lever in position for maintaining engagement of either clutch or neutral position of the lever, when the lever has been operated for desired position of the clutch. A link 159 is articulated with the 75 lever 149 and with an operating handle 160, pivoted to the wringer-frame. (see Figs. 3 and 4.)

The wringer-arm is arranged to be placed in a position between the oscillating tubs or 80 in a position crosswise of either tub and may, if desired, be swung entirely out of range of the tubs. It is arranged to be clamped in place in any of its assumed positions by means of a clamp, instanced as 85 acting between the bearing-sleeve 127 and the bushing 122. (See Figs. 13, and 14.) The clamp is shown as a plug 161 received in a bore 162 in the wringer-arm and provided with a concave face 163, concentric 90 with the axis of rotation of the shaft 121, to form a shoe-bearing against the bushing.

The plug is provided with cam-faces 164. Co-acting cam-faces 165 are on a collar 166, from which an arm 167 extends for operating the collar. The collar 166 and the cam-faces thereon rock about an axis at right angles to said shaft 121. A bolt 168 passes through the collar and plug and a bearing 169 in the wringer-arm. The bearing, plug 100 and collar are located between the head of the bolt, and a nut 170 thereon, a jam-nut 171 fixing the adjusted relation of the parts. The bolt and nut are so adjusted as to cause 105 secure clamping together of the plug and bushing when the arm 167 is operated to turn the collar for moving the cam-faces 165 thereon across the cam-faces 164, the clamping action being released upon opposite movement of the clamp-arm. The means described forms a cheap and simple clamping device readily assembled for the purpose stated. The adjustment of the bolt may be such that full clamping force may be applied by a movement of the clamp-arm 110 through a comparatively small arc of the circle.

Means are provided for operating the clamp from a position at the outer end of the wringer-bracket, as by providing an endwise movable rod 172, (see Figs. 3 and 4), articulated at 173 with the arm 167 movable endwise in a bearing 174 on the wringer-bracket. The rod has a handle 175 at its outer end for moving the same in either 115 direction.

Suitable balance-springs are provided for the tub, shown as balance-springs 181 whose ends respectively are hooked about hooks 182 pivoted to arms 183 and about lugs 184. 130

The tubs have openings 191 closed by suitable covers 192 having suitable handles 193. A drip-board 194 has ends 195, 196, and is located between the side-posts 197 of the 5 wringer and between a cross-piece 198 and the bracket 136, stops 200 coacting with the bracket. Deflecting pieces 201 having deflecting faces 202 coact with the respective ends of the drip-board to lead the same to 10 the tub-openings.

By means of the gearing mechanism, a compact, simple and effective arrangement of gearing is provided for operating either one or both tubs, the operation of the tubs, 15 when both tubs are operated, being in unison. Durable means are provided for positioning the wringer-arm into desired radial relations and clamping the wringer-arm in assumed radial positions, and for operating 20 the wringer-rollers in either direction in any of its assumed positions and for controlling the rotation or non-rotation of the wringer-rollers by novel and effective mechanism suitably placed in convenient position for 25 the operator distanced from the gearing.

The driving means employed are further extremely simple employing few gears and requiring a substantially minimum amount of power for operating the same.

Having thus fully described my invention, 30 what I claim as new and desire to secure by Letters Patent, is:

1. In a device of the character described, the combination of a main frame, a column 35 extending upwardly therefrom, said column comprising an upwardly extending journal bushing, a sleeve-bearing about said journal bushing having a central bearing-bore rotating about said journal bushing, the said 40 bearing-bore extending upwardly beyond said journal bushing, the upper end of said sleeve-bearing being reduced in cross-section, said reduced portion spaced from the upper 45 end of said journal bushing by a section of said bearing-bore, and a laterally extending wringer-bracket on said sleeve-bearing, the lower end of said sleeve-bearing and said column at the lower end of said journal bushing respectively provided with coacting 50 laterally extending annular flanges having mating bearing faces forming a step-bearing between said sleeve-bearing and said journal bushing, and the upper end of said journal bushing being spaced from the upper end 55 of said bearing bore for locating said upper end of said journal bushing free of end-contact with said sleeve-bearing in said bearing-bore, and a friction-clamp between said sleeve-bearing and said journal bushing to 60 frictionally hold said sleeve-bearing and said journal bushing together.

2. In a device of the character described, the combination of a column, a wringer-supporting bracket swingable thereon, a 65 drive-shaft in said column about which said

bracket swings, a bevel-gear at the upper end of said drive-shaft, a cross-shaft for operating the wringer-rollers, opposed bevel-gears loose thereon meshing with said first-named bevel-gear, a clutch between said 70 cross-shaft and said pair of bevel-gears for operatively connecting either of said last-named bevel-gears with said cross-shaft for operating said wringer rollers selectively in reverse directions, a clamp for clamping said 75 bracket to said column in adjusted positions comprising a shoe on said bracket having a concave clamping face concentric with said shaft coacting with said column, and a lever on said bracket, said shoe and lever provided with coacting cam-faces having axes at right angles to said shaft, whereby to clamp said shoe to said bracket.

3. In a device of the character described, the combination of a column, a wringer supporting bracket swingable thereon, a drive-shaft in said column about which said bracket swings, a bevel-gear at the upper end of said drive-shaft, a cross-shaft for operating the wringer-rollers, opposed bevel-gears loose thereon meshing with said first-named bevel-gear, a clutch between said last-named shaft and said pair of bevel-gears for operatively connecting either of said last-named bevel-gears with said cross-shaft for 90 operating said wringer-rollers selectively in reverse directions, a clamp for clamping said bracket to said column in adjusted positions comprising a shoe on said bracket having a concave clamping face concentric with said shaft coacting with said column, a lever on 95 said bracket, said shoe and lever provided with coacting cam-faces having axes at right angles to said shaft whereby to clamp said shoe to said bracket, a stem connecting said 100 lever, shoe and bracket, and adjusting means therefor whereby to regulate the clamping effect of said shoe.

4. In a device of the character described, the combination of a frame, a column extending upwardly therefrom, said column comprising a bushing, a sleeve-bearing about said bushing extending upwardly above said column, a laterally extending wringer-bracket on the latter, the lower end of said 110 column and the upper end of said sleeve-bearing provided with shaft-bearings, an upright shaft in said shaft-bearings, a bevel-gear fixed to the upper end of said shaft, continuously rotating driving means fixed 115 to the lower end of said shaft, a cross-shaft journaled in said wringer-bracket, a pair of bevel-gears normally loose thereon meshing with said first-named bevel-gear, an axially movable clutch about said cross-shaft between said bevel-gears for operatively connecting either of said bevel-gears with said 120 cross-shaft, arranged to rotate said cross-shaft selectively in reverse directions, an axially movable bearing-plug between said 125 130

sleeve-bearing and said bushing provided with an arc-face coacting with said bushing, said arc-face being concentric to the axis of rotation of said shaft, and cam means for 5 clamping said plug to said bushing.

5. In a device of the character described, the combination of a main frame, a column extending upwardly therefrom, said column comprising an upwardly extending journal 10 bushing, a sleeve-bearing about said bushing having a central bearing-bore, the said bearing-bore extending upwardly beyond said journal bushing, a laterally extending wringer-bracket on said sleeve-bearing, the 15 lower end of said sleeve-bearing and said column at the lower end of said journal bushing respectively provided with coacting laterally extending annular flanges having mating bearing faces forming a step-

bearing between said sleeve-bearing and said journal bushing, the upper end of said journal bushing being free of end-contact with said sleeve-bearing in said bearing-bore, a bearing-plug between said sleeve-bearing and said journal bushing, said bearing-plug provided with an arc-face concentric with said journal bushing and coacting with said journal bushing, and cam means on said sleeve-bearing arranged to press said bearing-plug 25 axially for clamping said sleeve-bearing and 30 said journal bushing together.

In testimony whereof, I have hereunto signed my name in the presence of two subscribing witnesses.

ROBERT J. ANDERSON.
